UNITED STATES PATENT OFFICE.

WILLIAM JACKSON MERRILL, OF PHILADELPHIA, PENNSYLVANIA.

GOLF-TEE.

1,194,860.

Specification of Letters Patent. Patented Aug. 15, 1916.

Application filed December 3, 1915. Serial No. 64,796.

To all whom it may concern:

Be it known that I, WILLIAM JACKSON MERRILL, a citizen of the United States, and a resident of Philadelphia, county of Philadelphia, State of Pennsylvania, have invented a certain new and useful Golf-Tee, of which the following is a specification, reference being had to the accompanying drawing.

10 My invention relates to devices applicable to the game of golf as at present played, and is designed to supersede the use of a small mound of sand, earth or other material which at certain stages of the game is 15 formed or erected by the player as a base or pedestal upon which the ball with which the game is played is mounted preparatory to striking same with a suitable golf club.

For the purpose of providing a convenient 20 means of forming the mound or pedestal referred to and which is known as a "tee", it is customary in most golf clubs to provide a box of moist sand at the points upon the course where it is customary for the players 25 to drive the ball from a tee, and the player, preparatory to making a stroke, generally manually withdraws sufficient of the sand from the box to form a tee of the desired size and then placing the sand upon the 30 ground, compresses the same between his fingers to form a substantially cone-shaped mound, upon the apex of which he places the ball. Under varying conditions and with different players it is customary to vary the 35 height of the tee as desired, some players preferring a tee of relatively low height and others a tee of greater elevation, depending upon the individual method of play and the nature of the stroke to be made.

40 The construction of the earth or sand tee as hereinbefore described, is at best a somewhat annoying and disagreeable operation, involving as it does the withdrawal of the moist sand from the box or the gathering of 45 a sufficient amount of earth from any suitable or convenient place should the box by any chance be empty, whereby the hands of the player become soiled. Furthermore, to properly construct the tee and balance the 50 ball thereon requires a certain amount of skill, and if the sand or earth used for the purpose is not properly moistened considerable difficulty is often experienced in causing the tee to assume the desired shape and 55 height and in positioning the ball thereon.

A principal object of my invention, there-

fore, is to provide an artificial golf tee which may be carried about the golf course by the player for convenient employment at such points thereon as may be desired; to provide a tee of this nature which shall be readily adjustable in height and which if accidentally struck by the club in making the stroke will in no wise injure the same, or be likely to be driven for a considerable distance in case it should be so accidentally struck.

Further objects of my invention are to provide a golf tee having the foregoing characteristics, which shall be of pleasing appearance, which shall possess all of the advantages of the tee formed of sand or other material and none of the disadvantages as hereinbefore briefly outlined, and which may be constructed at minimum expense and sold for a low price.

My invention further includes all of the other various novel objects and features of construction and arrangement hereinafter more definitely specified.

In the accompanying drawing is illustrated a preferred form of my invention, Figure 1 being a perspective view of the device in operative position; Fig. 2 another perspective view thereof in a modified operative position, and Fig. 3 a central vertical longitudinal section of the device.

That form of the invention illustrated may preferably comprise a plurality of superimposed plies 1 of suitable preferably 90 slightly resilient material, and in practice I prefer to form the plies of leather, fiber, rubber or the like. Each ply, of which there may be any desired number, six being shown in the drawing, may comprise disks 3, 4 at 95 either end connected by a longitudinally extending bar 5, the diameter of the disk 3 of any given ply being preferably somewhat greater than the diameter of the disk 4. Preferably circular apertures 7 are formed 100 in each of the disks 3, these apertures, if desired, being all of the same size, but the outside diameter of each of the disks 3 may preferably be graded or graduated, that of the disk 3 in the uppermost ply being 105 slightly less than the diameter of the corresponding disk of its subjacent ply, and so on in succession, so that when the plies are assembled as shown in Fig. 1, the superimposed disks 3 will form substantially a frustum of a cone having a central, substantially cylindrical aperture. In a similar manner

the diameters of the disks 4 of the several plies are made increasingly greater from the uppermost ply to the lowermost ply, so that these several disks when the plies are assembled will also constitute substantially a frustum of a cone.

For the purpose of securing all of the plies in relatively rotatable relation, suitable means are provided adjacent the disks 4, 10 those shown in the drawing comprising a suitable headed rivet 10 extending through suitable apertures in the plies and a preferably circular washer 12 surrounding that portion of the rivet extending below the 15 lowermost ply and preferably of somewhat greater diameter than the lowermost disk 4, the lower end of the rivet being headed over either directly against this washer or against the smaller washer 15 interposed between 20 the under face of the washer 12 and the headed over portion of the rivet. It will be evident that if the rivet be formed of a suitable length, the various plies will be by 25 this means secured together in superimposed relation and also be capable of relative rotation about the rivet as a center for the purpose to be hereinafter described.

If desired all of the plies may be made of constant thickness, but in the preferred 30 form of the invention and as shown in the drawing, I preferably taper or graduate the thickness of each ply from the end comprising disk 3 toward the end comprising disk 4 in such manner that each ply adjacent the rivet will be considerably thinner than adjacent the aperture 7, so that when 35 the various plies are assembled, as best shown in Fig. 3, this graduation or thinning of the thicknesses of the individual plies 40 will result in an increased height of the plies so assembled adjacent the aperture 7 over the height of the assembled plies adjacent the rivet 10 as clearly shown in the drawing.

The operation of the device, which it is 45 thought will be almost self-evident from the drawing, may be described as follows: The tee may be readily carried by the player during the progress of the game, and on reaching a point upon the course at which 50 it is desired to make use of the tee as a base or pedestal to elevate the golf ball preparatory to striking the same with the golf club, the tee may be placed upon the ground as shown in Fig. 1 with the lowermost ply and 55 washer 12 in contact therewith, that end of the tee carrying the rivet being preferably turned farthermost from the player in the position which is assumed preparatory to striking the ball. The ball 20 may then be 60 placed upon the frustum of a cone formed by the several disks 3, the aperture 7 in the uppermost disk being preferably of such size that the surface of the ball will project therein for a short distance so as to steady 65 the ball upon the tee. The ball being thus

elevated is now ready to be driven from the tee with a club in the usual manner, and owing to the relatively small diameter of the aperture 7 with respect to the diameter of the ball 20, whereby the ball is prevented 70 from entering except for a very short distance into the aperture, the ball when struck will leave the tee cleanly and without carrying the same along with it for any appreciable distance. Moreover, in consequence 75 of that portion of the tee adjacent the ball being higher than any other portion, due to the tapering or thinning of each ply toward that end adjacent rivet 10, there is very little likelihood of the club striking 80 the tee, even if it be swung a little too low, but even if the tee be accidentally struck in making the stroke it is not apt to be driven more than a few feet from the player owing to its peculiar shape and, in addition, on account of the tee being formed of leather or other preferably slightly resilient material 85 it will not readily be injured by contact with the golf club or, in turn, injure the club in any way.

In case for any reason such as the individual method of play adopted, or the nature of the stroke to be made, the player prefers a lower elevation for the ball than that secured when the ball is placed upon 90 the tee as shown in Fig. 1, any desired number of plies may be turned to one side and the ball 20 rested upon the remaining plies as shown in Fig. 2, instead of upon the uppermost ply as shown in Fig. 1, thus securing, within limits, any desired elevation for the ball. Since the aperture 7 in any of the disks 3 is preferably of the same size as that in any other disk, the action of the ball in leaving the tee from a position upon any 100 one of the intermediate disks, for example from the third disk from the bottom as shown in Fig. 2, will be exactly the same as when the full height of the tee is utilized and the ball positioned upon the uppermost 105 ply as hereinbefore described, and as the plies not employed to support the ball are turned back out of the way they in no manner whatsoever interfere either with the ball leaving the tee or with the stroke of 110 the player.

It will be evident owing to the preferred method of graduating the diameters of the disk so that when vertically axially aligned they will form substantially frustums of 115 cones with their greatest diameters adjacent the bottom at either end of the tee, that the tee will tend to remain constantly upright after being placed in position, both when utilized to obtain the greatest elevation for the ball, as shown in Fig. 1, or when arranged to present a lower elevation, as shown in Fig. 2, the weight of the washer 12 also assisting in securing this result, and that in consequence a steady, true and secure support of 120

known height is afforded for the ball, a matter tending to materially aid in the execution of the stroke made by the player.

While I have illustrated and described in some detail a preferred form of my invention, I do not desire or intend to thereby limit myself specifically thereto, as it will be evident that various changes may be made in the details of construction and arrangement of the various parts of the device, and that the size and shape thereof may be altered, and other suitable modifications made without departing from the spirit and scope of the invention as defined in the appended claims.

Having thus described my invention, I claim and desire to protect by Letters Patent of the United States:

1. A golf tee comprising a series of tapering bars formed and arranged to lie flat with respect to each other in superimposed relation and selectively revoluble about a

common center, each bar being adapted to support a golf ball adjacent the end thereof removed from said center.

25

2. A golf tee comprising a series of tapering bars formed and arranged to lie flat with respect to each other in superimposed relation, each bar being capable of revolution about a common pivot positioned adjacent an end thereof and adapted to support a golf ball adjacent the opposite end thereof.

30

3. A golf tee comprising a series of tapering bars formed and arranged to lie flat with respect to each other in superimposed relation each bar having a disk adjacent one end thereof adapted to support a golf ball, and a pivot passing through said bars adjacent the ends thereof opposite to said disks, said bars being capable of selective revolution about said pivot.

35

In witness whereof, I have hereunto set my hand this first day of Dec., A. D., 1915.

WM. JACKSON MERRILL.
